FUSE TUBE ADAPTER

Alwin G. Steinmayer, Milwaukee, Wis., assignor
to Line Material Company, Milwaukee, Wis., a
corporation of Delaware

Application August 7, 1946, Serial No. 688,815

2 Claims. (Cl. 200—120)

1

This invention relates to a fuse tube adapter.

It is a well known fact that large capacity fuse tubes must, of necessity, have a large bore in order to accommodate the fusible element and leader and also to provide the necessary rupturing capacity.

It frequently happens that purchasers when they first install the fuse tubes on their distribution lines, do not need the large capacity fuse tubes, but they anticipate subsequent developments, which would necessitate the large fuse tube with the high rupturing capacity. If on the one hand they install small fuse tubes for low rupturing capacities, they would have to discard this equipment and install larger fuse tube assemblies when their customers had increased in number. On the other hand, if they install large fuse tubes, with high rupturing capacities and used small fuse links with these fuse tubes, they would run the danger of failing to build up a sufficient compression in the tube to rapidly extinguish the arc and the arcing time might be sufficiently long to cause total destruction of the fuse tube and the associated parts.

This invention is designed to provide a fuse tube adapter which will permit the initial purchase and installation of large capacity fuse tubes but which when placed within such large capacity fuse tubes will alter the action of the fuse tube so that it may be used with small capacity fuse links with the assurance that the fuse tube will completely and quickly clear itself on overload.

Further objects are to provide a very simple type of fuse tube adapter which is cheap to make and which is easily installed in a large capacity fuse tube, and which is so constructed that it will take a simple type of fuse link or a fuse link provided with a small permanently installed fiber or other tube, and which is so made that if an abnormally large overload occurred and the adapter itself is ruptured, no damage will be caused to the main fuse tube assembly as this large overload would generate sufficient compression to quickly extinguish any arc that might be formed.

An embodiment of the invention is shown in the accompanying drawings, in which—

Figure 1 is a fragmentary view partly in section showing the adapter in place.

Figure 2 is an enlarged fragmentary view of a section of the upper portion of the structure shown in Figure 1.

Referring to the drawings, it will be seen that a standard type of drop-out fuse assembly has been shown although the adapter is applicable

for use in any type of fuse tube, whether of the drop-out kind or of some other type. The main fuse tube illustrated in the drawings, may be similar to that disclosed in the patent to Schultz and Steinmayer, No. 2,176,227 of October 17, 1939, for Combined switch and fuse, assigned to the assignee of the present application. This fuse tube is indicated by the reference character 1 and may be of relatively high rupturing capacity 5 with a relatively large internal bore. It is provided with an upper terminal 2 and a lower terminal assembly indicated generally at 3 against which the upper brush contact 4 and the lower brush contact 5 respectively bear. The fuse link 10 may comprise any type of link construction. In the form chosen for illustration, the fuse link comprises a fusible section 6 and a strain wire 7, which are joined at their upper ends through the member 8 to a buttonhead 9 and at their 10 lower ends to a flexible leader 10. The fuse link also preferably, though not necessarily, may have a small fiber tube 11 formed as a unitary part of the fuse link assembly. This construction is similar to one of the forms of the invention 15 shown in the patent to Brown, No. 2,382,602 of August 14, 1945, for Fuse link, assigned to the assignee of this application.

It is customary to provide a washer 12 which loosely receives the shank 13 of the buttonhead 20 30 9. The buttonhead 9 is clamped in place by means of the screw cap 14 forming a portion of the upper terminal of the fuse tube assembly. The flexible leader 10 extends downwardly through the open lower end of the expulsion 35 fuse tube 1 and is attached to a supporting lever 15 pivoted as indicated at 16 on the member 17 rigid with the fuse tube 1. The lower end of the lever 15 is provided with trunnions, not shown, pivoted in the lower stationary terminal 19 as 40 shown particularly in the Schultz et al patent hereinabove referred to. As stated, any other type of fuse tube assembly, provided it is an expulsion type, can be used.

The adapter comprises a tube 20 of insulating 45 material, preferably of fiber, whose end is received in an upper metal fitting 21, which is crimped or otherwise firmly secured to the tube 20. This upper fitting or contact member 21 is provided with an upper flange 22 which rests 50 in place upon the upper terminal 2 and which supports the washer 12 of the buttonhead 9 of the fuse link. The fiber tube 20 extends only part way downwardly within the main fuse tube 1 as particularly shown in Figure 2. As a specific example, though the invention is not limited

to these values, the interior bore of the adapter tube 20 may be of such a size as is customarily used with a 50 ampere fuse link, whereas the interior bore of the main tube 1 may be of a value customarily used with a 200 ampere fuse link.

In practicing the invention, assuming that the purchaser has installed a large rupturing capacity main fuse tube 1 to take care of anticipated increases in the load on the distribution line but wishes to use a relatively smaller capacity fuse link, he merely places the adapter 20 in the upper end of the fuse tube 1. A small size fuse link is threaded through the adapter and the main fuse tube 1 and the cap 14 of the main fuse tube is screwed into place. The cap 14 not only clamps the buttonhead of the fuse link, but also clamps the adapter in place.

It is obvious that if any overload of about the normal capacity of the fuse link occurs, the multiple tube construction will readily clear itself as sufficient compression will build up within the adapter 20 to insure proper ejection of the remaining portion of the fuse link and quick extinction of the arc. If a small overload occurs with the particular type of fuse link employed, the small fiber tube 11 of the fuse link assembly will insure building up of proper compression within the small fiber tube 11 itself to insure extinction of the arc and proper ejection of any remaining portion of the fuse link.

On the other hand, if any abnormally large overload occurred, of such a value that it might rupture the adapter 20 and most certainly rupture the small fiber tube 11, no damage would result as sufficient compression would build up in the main fuse tube 1 to insure extinction of the arc and ejection of any remaining portion of the fuse link.

Thus it will be seen that a multiple fuse tube construction has been provided which will properly function for overloads of widely different values from a relatively small overload to a relatively heavy overload far in excess of any for which the particular fuse link is intended without any damage to any part of the main fuse tube assembly itself.

Further than this, the adapter is a relatively inexpensive member cheaply produced and easily installed and it is of practically no consequence so far as expense is concerned to discard all of the adapters on a distribution line or such of them as is necessary, when the development supplied by the distribution line has increased to such a value that the large capacity fuse link may now be employed. Thus it is possible for a customer to initially install large capacity fuse tube assemblies on his distribution line and continue to use these although the load on the line does not at the time of installation warrant such large size fuse tube assemblies. On the other hand, when the load on the line has developed to a point sufficient to warrant the use of the

large rupturing capacity installation, the adapters are merely discarded with very minor expense to the customer and the large size fuse links are used. Ordinarily, it is intended that the adapter be used over and over, the ruptured fuse alone being replaced.

Although this invention has been described in considerable detail, it is to be understood that such description is intended as illustrative rather than limiting, as the invention may be variously embodied and is to be interpreted as claimed.

I claim:

1. A fuse tube assembly comprising a main outer insulating tube open at both ends and having a terminal provided with a closure cap for closing one end of said main tube, an inner insulating tube open at both ends and constituting an adapter located within said main tube and having a flange at one end adjacent the closure cap and arranged to be supported solely from the terminal of said main tube and clamped in place by said closure cap, and a fuse link having an enlarged head free from attachment to said inner tube and arranged to be clamped between the flange of said inner tube and the closure cap of said main tube and having a fusible section located within said inner tube and a flexible leader extending from the fusible section outwardly through both said main and inner tubes.
2. A fuse tube assembly comprising a main outer insulating tube open at both ends and having a terminal provided with a closure cap for closing one end of said main tube, an inner insulating tube open at both ends and constituting an adapter located within said main tube and having a flange at one end adjacent the closure cap and arranged to be supported solely from the terminal of said main tube and clamped in place by said closure cap, and a fuse link assembly having an enlarged head free from attachment to said inner tube and arranged to be clamped between the flange of said inner tube and the closure cap of said main tube and having a fusible section located within said inner tube and a flexible leader extending from the fusible section outwardly through both said main and inner tube, said fuse link assembly having an insulating tube surrounding the fusible section and located within said inner tube.
